UNITED STATES PATENT OFFICE.

HENRY T. PAISTE, OF PHILADELPHIA, PENNSYLVANIA.

INSULATING-LINING FOR INCANDESCENT-LAMP SOCKETS.

SPECIFICATION forming part of Letters Patent No. 692,700, dated February 4, 1902.

Application filed June 8, 1901. Serial No. 63,682. (No model.)

To all whom it may concern:

Be it known that I, HENRY T. PAISTE, a citizen of the United States, residing in Philadelphia, Pennsylvania, have invented certain Improvements in Insulating-Linings for Incandescent-Lamp Sockets, of which the following is a specification.

My invention relates to certain improvements in insulating-linings for electric-lamp fixtures, and more particularly to an improved form of insulating shell or lining for incandescent-lamp sockets.

The object of my invention is to provide an insulating-lining for the interior of the brass shell which ordinarily forms the cover or support of a lamp-socket, which shall be cheaper to manufacture and at the same time fit its brass shell more accurately than the insulating-bushings hitherto made. These objects 20 I attain as hereinafter set forth, reference being had to the accompanying drawings, in which—

Figure 1 is a plan view of the blank from which my insulating-shell is made. Fig. 2 is 25 a perspective view of a finished insulating-shell as it come from the forming-machine. Fig. 3 is a similar view of a shell, showing its vertical edges brought together in the position occupied when it is within a brass socket-shell; and Fig. 4 is a vertical sectional view 30 of my improved insulating-shell.

As hitherto manufactured insulating-bushings for lining the interior of incandescent-lamp sockets have been formed from a cylindrical section of fiber tubing, this being forced, 35 by means of a plunger, into a die which crimped or corrugated its lower half, so as to reduce its diameter while preserving a cylindrical form. The shell so formed consisted, 40 therefore, of two cylindrical sections of different diameters connected by an inclined section forming a shoulder, and the smaller of these sections was necessarily quite rough in form, owing to the crimping. In addition to 45 the rough appearance of this finished article the insulating-tubing from which it was formed was, owing to difficulties incident to its manufacture, comparatively costly.

In my improved lining or shell I first, by 50 means of any suitable machine, stamp from a piece of sheet fiber a piece similar in form to that shown in Fig. 1 at A. This piece is

the approximate shape of an unrolled or developed lining or shell, being made with its bottom edge a slightly curved or bent, as illustrated—that is to say, of such configuration that when the sheet is rolled up and formed the ends of said sheet will perfectly meet in a line. The edges a^2 of the upper part of its ends are cut at right angles to the top edge a' ; but the edges a^3 of the lower part of said ends are cut inwardly by an amount depending upon the diameter of the lower section of the finished shell. If desired, recesses a^4 may be cut in the edges of the sheet A at the same time that said sheet is stamped from the sheet of raw material. This sheet A is now placed in a special machine, for which I have made application for United States Letters Patent under date of March 18, 1901, Serial No. 51,683, 70 allowed June 6, 1901, and by means of it is drawn and bent into the form shown in Fig. 2, the plunger of said machine forming the lower section b of the lining or shell A as a perfectly-smooth cylinder, united to the upper section b' by a smooth curved shoulder b^2 . As delivered from the forming-machine the shell springs apart, as shown in Fig. 2; but when pressed into a brass socket-shell its edges a^2 a^3 come together in a straight line, as 80 indicated at a^5 in Fig. 3.

It will thus be seen that by the use of sheet material I am enabled to construct a shell or lining of a more perfect form and one which consequently occupies less space than has 85 hitherto been the case in the art. In addition to this I utilize sheet fiber or other insulating substance in the manufacture of these linings, a form of raw material not hitherto practically available, although one which is de- 90 cidedly less costly than the fiber tubes formerly employed.

It has been found in use that my improved form of split insulating shell or lining is superior to the tubular shell before used, as it 95 can be made to more accurately conform to the shape of the interior of a lamp-socket. Being perfectly smooth in outline, without wrinkles or corrugations, it occupies comparatively less space than the said tubular 100 form of lining in a receptacle in which space is a valuable consideration.

I claim as my invention—

1. As a new article of manufacture, an in-

5 insulating-shell for a lamp-socket having two connected cylindrical sections of different diameters, the same consisting of an elongated, rolled-up sheet of insulating material, one edge of said sheet being equal in length to the circumference of one section of the shell and the opposite edge of the sheet being continuous and of such a length and configuration that when the sheet is rolled up and 10 formed, the ends of said sheet will perfectly meet in a line, substantially as described.

2. A blank from which an insulating-bushing is to be formed, the same consisting of a piece of sheet material, one edge thereof be-

ing straight and having recesses therein, the 15 opposite edge being a bent line and the edges of the ends being each cut in lines at an angle to each other, one of said lines being at right angles to the straight edge of the blank, substantially as described.

20 In testimony whereof I have signed my name to this specification in the presence of two subscribing witnesses.

HENRY T. PAISTE.
